HEATER

Ambrose D. Olds, Wichita, Kans.

Application May 18, 1934, Serial No. 726,202

2 Claims. (Cl. 126—116)

This invention relates to heaters and particularly to that class known as floor furnaces wherein the furnace is set in a floor with the top flush therewith, and the furnace proper extending below the floor. The primary object of the invention is to increase the efficiency of floor furnaces, that is to construct a furnace in which more air can be handled through the furnace than is generally possible with known types of devices.

5 Floor furnaces have been used prior to my invention but all the constructions of which I have any knowledge have certain inherent disadvantages. For example, the success of a device of this kind depends to a large extent upon the ability of the device to handle a relatively large quantity of air passing through it. If the air flow is retarded, the thermal efficiency of the furnace is decreased, but if a relatively large amount of air can pass through the furnace in unobstructed flow, the furnace will become more efficient, so 10 I have provided means whereby the maximum amount of air will be handled.

15 Another important feature of the invention resides in the fact that the inlet to the cold air chamber which discharges into the heating chamber will be relatively large as compared with the remaining cross-section of the cold air chamber so that the cold air will readily flow from the floor into the cold air chamber and the warmed air instead of being discharged from the furnace 20 in parallel stream lines will have its stream-lines bent inwardly or upwardly so that some of the stream lines will contact with others to spread the heated air in what might be termed a broad 25 angular spray so that the air will be diffused over a relatively wide area, thus more efficiently heating the room than would be possible if the hot air flowed through in vertical stream lines toward the ceiling where it would be liable to stratify instead of being diffused over the floor 30 space which is the most important part of the room to heat.

The cold air chamber has a top air inlet and a curved bottom to bend the air stream lines 35 in a reverse direction to counterflow up through the heating chamber to induce a free unobstructed flow of air through the furnace whereby the maximum amount of air will pass by and through the heating zone.

40 The casing for the heating chamber has a constricted outlet with inwardly sloping walls to provide a relatively wide entrance opening for the air chamber which surrounds it. This permits the easy entrance of the air into the furnace and 45 diverts the upflowing stream lines of hot air so

that they are directed inwardly to cause a certain amount of agitation destroying their parallelism to thus insure diffusion of the hot air in a relatively large area in the room.

5 There are other novel features of the invention, all of which will be specifically described hereinafter, reference being had to the accompanying drawing in which:

Figure 1 is a perspective view of the furnace embodying my invention, parts being broken away 10 to better illustrate certain other parts;

Figure 2 is a fragmentary sectional view through part of the cold air chamber, and

Figure 3 is a similar view through the opposite wall of the cold air chamber showing the burner. 15

Referring now to the drawing by numerals of reference, 1 designates the floor of a room in which the furnace is to be installed, and 2 designates the joists or other supports to which the casing, forming the cold air chamber, is secured. 20

The outer casing 3 is provided with four vertical walls 4, 5, 6, and 7, with inwardly and upwardly curved lower edges 8, preferably in the form of a part of a spiral surrounding a floor 9. The upper edges of the walls surround a space 25 10 covered by a register or cover 11.

Within the casing 3 is a heating chamber consisting of a shell having walls 12 and 13 held in spaced relation by the channels 14 to provide an insulating space 15, the bottom of the heating 30 chamber being open and spaced above the curved edges 8 so that the cold air may enter said heating chamber while the upper part of the heating chamber carries a constricted open ended outlet 15 with inwardly sloping walls to prevent parallel upflow of the hot air causing the stream lines of the hot air to bend inwardly to impinge one upon another and thus diffuse them over a relatively large area. The inwardly sloping walls of the outlet 15 also form a relatively large inlet 16 for the cold air. The heater within the heating chamber includes a suitable burner 17 supplied with fuel from a suitable source such as gas, through a pipe 18, having a T connection 19 to which a pilot burner 20 is connected by a pipe 21, 45 the burner 17 being connected to the T connection through a pipe 22. The two pipes are provided with valves 23 and 24.

The combusted gases pass up through an elongated rectangular heater casing 25 having a 50 transparent cover 26 so the burner will be visible through the wall of the burner casing. The products of combustion discharge through a pipe 27 into a downdraft elongated enclosing rectangular radiator 28 having a discharge pipe 29 adapted to 55

be connected to a chimney or flue in any well-known manner.

A hot air flue 30 open at its ends, passes through the radiator and discharges into the hood 15, it being understood that the cold air passes around the radiator and around the heater casing as well as through the flue 30 and that the casing 25 is spaced from the walls 14 by the partitions or fins 31 which terminate short of the top and bottom of the cold air casing. In actual practice the lower part of the casing 3 may be secured to the vertical walls by a lap joint 32. The actual construction of the casing 3 however, may depart from that shown.

15 The curved lower edges of the side walls of the outer casing are an important feature of my invention since they prevent the down coming air forming eddy currents at the bottom of the cold air space which would so restrict the flow of 20 the air at the corners that the efficiency of the furnace would be materially affected. By making it possible to reverse the flow of the air from the cold air passageway to the heater space or chamber, a large volume of air will pass through the 25 furnace and the efficiency of the furnace will be increased.

I claim:

1. In a floor furnace an outer casing having an open top and closed bottom, an inner casing open at the top and bottom and spaced from the sides and bottom of the outer casing, and a heater within the inner casing, the marginal portions of the bottom of the outer casing being of upwardly opening trough shape, said portions extending below the lower edge of the inner casing to points inwardly of the inner casing whereby to direct the down flow of air between the inner and outer casings in curving stream lines into the space between the inner casing and the heater. 5

2. In a floor furnace an outer casing forming an air chamber, said chamber having an open top and closed bottom, an inner casing open at the top and bottom and spaced from the sides and bottom of the chamber, a heater within the inner casing, the marginal portions of the bottom of the chamber being of upwardly curving trough shape, said portions extending below the lower edge of the inner casing to points inwardly of the inner casing whereby to direct the down flow of air between the inner and outer casings in stream lines into the space between the inner casing and the heater. 10 20 25
